MERCHANDISING DRAWER ASSEMBLY
Paul K. Fuller, Rocky River, Ohio, assignor to The Fullwell Motor Products Co., Inc., Cleveland, Ohio, a corporation of Ohio

Filed Dec. 19, 1960, Ser. No. 76,646
1 Claim. (Cl. 312—336)

This invention relates to a new and improved slidable drawer assembly and more particularly to a drawer assembly especially designed for use in periodically dispensing merchandisable materials therefrom.

In the handling of material wherein the same is temporarily deposited in a drawer container or enclosure, for example materials such as nuts, bolts and the like, and thereafter a plurality of which is periodically dispensed from said enclosure and the remaining supply likewise replenished, it is desirable to have the complete drawer enclosure accessible so that all of its interior may be readily utilized and/or the contents therein available for convenient selection. This is of further importance when the drawer container or enclosure is provided with a movable cover which, when disposed over the open end thereof is intended to protect the contents disposed therein, and it is thereafter required to remove the aforesaid drawer enclosure completely out of its accommodating cabinet so that said cover may be removed sufficiently to provide access to the complete interior thereof.

It is therefore a primary object of the present invention to provide a new and improved drawer assembly especially designed to enable periodic dispensing of materials therefrom and which includes a drawer or like container disposed within a cabinet chamber or the like, said assembly having means slidably supporting said drawer within said chamber and operable therewith to enable the said container to be moved completely into and/or out of said chamber.

Another object of the present invention is the provision of a novel and improved drawer assembly wherein said drawer is intended to be removably disposed within a cabinet chamber or the like, said assembly including a pair of nested slide members, said drawer being anchored to one of said slide members, said slide members being slidably movable relative to said cabinet and to one another, effective to carry the aforesaid drawer completely out of its accommodating chamber to thus provide access to the complete interior of said container.

Still another object of the present invention is the provision of a novel and improved drawer assembly especially designed to enable periodic dispensing of materials therefrom and which includes a drawer or like container disposed within a cabinet chamber, a pair of nested slide members, said drawer being anchored to one of said slide members, said slide members being slidably movable relative to said cabinet and to each other effective to carry the aforesaid drawer container completely out of said chamber, and means interconnecting said slide members and cabinet effective to limit the relative movement between the latter and said slide members.

Other objects and advantages of the drawer assembly of the present invention will be apparent to one skilled in the art to which it pertains and upon reference to the following disclosure of a preferred embodiment thereof and which is illustrated in the accompanying drawings wherein:

FIG. 1 is a front perspective view, being shown partially in section, of a drawer assembly embodying the concepts of the present invention;

FIG. 2 is a side perspective view showing the drawer supporting means actuatable to an extended position relative to the cabinet chamber so as to locate the drawer thereon completely out of the latter; and

2

FIG. 3 is an enlarged fragmentary horizontal sectional view taken approximately on the plane as is indicated by the lines 3—3 in FIG. 1.

Briefly, the novel and improved drawer assembly of the present invention, merely for purposes of the instant disclosure, is herein shown as especially designed for use in a cabinet or like housing, as is identified in its entirety by reference character C, said cabinet being substantially square prismatic in overall configuration and having an open vertical end as is indicated at 2 to provide access to its chamber 4.

Although the instant form of cabinet is provided with merely one chamber 4 for accommodating a drawer assembly, it is to be understood that said cabinet may have several or more chambers each accommodating a drawer assembly without departing from the inventive concepts hereof as will be hereinafter defined in detail.

The form of drawer or container D as is utilized with the cabinet C is of corresponding configuration being substantially box-like in its assembly and having a lid e hingably attached thereto at its one end and which is intended to be swingable upwardly from its closed position as is shown in FIG. 1 to its open position as shown in FIG. 2 to thus provide access into the interior of said drawer D.

The drawer or container D is supported upon a slide assembly as is identified in its entirety by the reference numeral 20, said assembly being thus intended to support the said drawer in said cabinet and to permit the same to be slidably movable completely into and/or out of the cabinet chamber 4.

With reference now directed particularly to FIG. 2, the instant embodiment of slide assembly 20 comprises an upper and a lower slide element 21 and 22 respectively, disposed in a nested relation, one to the other with the upper slide element being nested within said lower slide element.

The lower slide element 22 is seen to include a pair of rail members 23, each of which is somewhat L-shaped in end elevation to thus define a base leg 23a and an upstanding leg 23b, said base leg being securely fastened at the rear end thereof to one end of a brace member 25 the latter extending transversely therebetween.

The upper slide element 21 is also seen to have a pair of side rail members 28 securely attached at opposite ends thereof to a pair of end brace members 30, the latter extending transversely thereacross to thus form a substantially parallelogram construction for said slide element 21.

As before mentioned, the upper slide element 21 is nested within the lower slide element 22, the bottom edges of the side rail member 28 of said upper slide element preferably resting upon the upper surface of the underlying base leg 23a of the side rail members 23 of said lower slide element 22, and positioned so as to be slidably movable therealong.

The slide elements 21 and 22 of said slide assembly as thus far described are preferably fastened to each other so as to permit limited slidable relative movement therebetween.

For this purpose, the upstanding leg 23b of each of the rail members 23 of the lower slide element 22 is seen to be provided with a closed slot 35 extending partially centrally longitudinally therealong, and which is intended to slidably accommodate a pair of fasteners 38 mounted on the adjacent rail members 28 of the upper slide element 21 said fasteners being preferably spaced longitudinally therealong, and extending perpendicularly outwardly therefrom.

With this assembly, it is intended that the upper slide element 21 of the nested pair of slide elements may be

slidably moved over the lower slide element 22 of said assembly and into a plurality of positions thereon, said positional movement being thus limited depending upon the relative disposition of the aforementioned fasteners and preselected dimensions given each of the said slots 35.

The drawer or container D into which the dispensable materials are to be deposited is preferably of such dimensions as to be wholly accommodated within the upper slide member 21, being either set in, or rigidly attached thereto if desired, so as to be movable with the same.

The slide assembly 20 is seen to be disposed within the chamber 4 of the cabinet C, and is intended to be slidably movable therein so as to locate the container D completely within and/or out of said chamber. A handle h is mounted on the front edge of the container D to facilitate moving the same into and out of said cabinet.

Assuming that the drawer or container D is disposed completely within the cabinet chamber 4, the handle h may be pulled outwardly to initiate the movement of the same. During the initial movement of the drawer D the slide assembly preferably moves as an integral unit to an extended position such as is shown in FIG. 1.

To accomplish this, each of the rail members 23 of said lower slide element 22 is provided with an upstanding bracket 40 on its rearward end, each of said brackets extending upwardly in substantial co-planar relation to its associated side rail 23, being in addition, preferably formed at its upper end with a laterally inwardly projecting flange 40a.

A strap member 42 is rigidly attached to the inside surface of each of the side walls of the cabinet C, extending preferably centrally longitudinally therealong being formed at its front end, adjacent the open end of the cabinet chamber 4, with a reversely bent portion thus defining a U-shaped stop element 42a facing toward the closed end of said chamber.

The stop element 42a on each of said strap members 42 is so disposed that as the slide assembly moves outwardly of the cabinet chamber 4 during the initial slidable actuation thereof, the front vertical edge of each upstanding plate 40, as herein identified by the reference numeral 40b, is movable into said stop element 42a and into engagement with its closed end. When this occurs, the forward movement of the lower slide element 22 is thus stopped, this preferably occurring when only the rearward portion of the slide assembly remains within the cabinet chamber 4 as may be best seen in FIG. 2.

The aforementioned flange 40a formed on the upper edge of each of the said brackets 40 is disposed so as to preferably slidably engage the under surface of the top wall of the chamber 4 to thus prevent the slide assembly and attached container D from tipping downwardly as it is moved out of the said cabinet chamber.

With the lower slide element 22 thus stopped in its forward movement, the upper slide element 21 then continues in its outward movement, the fasteners 38 carried thereon moving through the slots 35 on the rail members 23 of said lower element to thereby locate the container D completely out of the cabinet chamber 4 whereby its lid may thereafter be swung upwardly to thus provide for access into the complete interior of said container.

As will now be apparent, as the container D is moved to its closed position so as to be completely within the cabinet chamber 4, only the upper slide element 21 preferably moves inwardly over the lower slide element 22 during the initial inward movement of said container.

Thereafter, as the fasteners 38 strike the inner closed

end of the aforesaid slots 35, said upper and lower slide elements 21 and 22 again move as an integral unit into the said cabinet chamber to thus position the container completely within the latter.

5 As best seen in FIG. 2, the bottom longitudinal edges of each of the aforesaid slide elements 21 and 22 may be formed respectively with an outwardly projecting guide rail 45 and a rail accommodating groove 46, each rail interfitting its adjacent groove to thus facilitate the smooth slidable actuation of said slide elements.

10 The aforementioned brackets 40 are each preferably formed of a flexible or bendable material so that, if desired, they may be flexed inwardly while spaced from the stop elements 42a, to thus move said brackets out of position for engagement with said stop elements, where-

15 after the lower slide element 21 and supported upper slide element 22 and container D may be removed from the chamber 4, said brackets moving past and inwardly of said stop elements during this interval. It will also be apparent that said assembly may be readily insertable into said chamber 4 by flexing said brackets inwardly and thus sliding the said assembly into said chamber.

20 Having described a preferred embodiment of merchandising drawer assembly, it is to be understood that said assembly is susceptible to various changes, combinations and arrangements of parts without departing from the inventive concepts thereof as are defined in the appended claim.

What is claimed is:

- 30 35 40 45 50 55 60
- In a cabinet having a chamber formed with an open end and a container disposed in said chamber; means for supporting said container and to permit said container to be slidably movable through said open end and completely into and out of said chamber, comprising a slide assembly disposed in said chamber and including a pair of nested slide members, the inner slide member of said pair having a pair of rails disposed in parallel spaced relation to each other, means for mounting said container on said rails, the outer slide member of said pair having a pair of spaced rails underlying said rails on said inner slide member, a flexible bracket on the innermost end of said underlying rails of said outer slide member, a strap member attached to the inside wall of said cabinet adjacent its open end and having a stop element extending into said chamber, said stop element being disposed in the path of said bracket and positioned for abutting engagement with the latter as said container is moved outwardly to an open position exteriorly of said chamber, a flange formed on said flexible bracket engageable with the cabinet wall defining said chamber preventing said container from tilting downwardly as it is moved out of said cabinet, and said bracket being bendable toward the center of said chamber to a position spaced inwardly from said stop element, said outer slide member being thereafter free to be slidably movable effective to move said bracket outwardly of and pass said stop element so as to enable said slide assembly and supported container to be removed completely from said chamber.
